UNITED STATES PATENT OFFICE.

ANDREW M. LOCKETT AND ANDREW M. LOCKETT, JR., OF NEW ORLEANS, LOUISIANA.

GAME APPARATUS.

1,086,189.

Specification of Letters Patent.

Patented Feb. 3, 1914.

Application filed August 5, 1912. Serial No. 713,324.

To all whom it may concern:

Be it known that we, ANDREW M. LOCKETT and ANDREW M. LOCKETT, Jr., citizens of the United States, residing at New Orleans, in the parish of Orleans and State of Louisiana, have invented certain new and useful Improvements in Game Apparatus, of which the following is a specification.

Our invention relates to simulated field games, where balls are thrown, batted, caught and transferred to any one of the players, where the runners may be advanced or returned to their bases, and the fielders located and movable upon the field to correspond with the ordinary conditions of the game, such as base ball and cricket.

The object of the invention is to provide an apparatus with which the games may be played as a game of skill, requiring practice to attain such proficiency, and thereby gain the interest of adults as well as children.

In previous devices of this character certain features of the game of baseball have been in a measure reproduced, but in all such apparatus of which we have knowledge the elements of chance has predominated, and their value has been insufficient, but in our game where skill of high order can be displayed, we believe the interest will increase rather than decrease and much innocent amusement be derived.

With our apparatus as adapted to the American game of baseball, a regulation game of baseball can be played and every act or move necessary to the complete carrying out of the game accomplished, with the one exception, that the players cannot run after the ball when a player fails to catch it by reason of an inaccurate throw, or a ball having been batted out of reach of the players.

The invention consists of structural features and relative arrangements of the several parts comprising the apparatus, which will be hereinafter more fully described and particularly pointed out in the appended claims.

In the drawings in which similar reference characters indicate the same parts in the several figures of drawing: Figure 1 is a plan view of the apparatus adapted for the game of base ball; Fig. 2 is a section on line 2-2 of Fig. 1, with the players removed; Fig. 3 is a section on line 3-3 of Fig. 1, with the players removed; Fig. 4 is an enlarged and fragmentary view of the

right hand end of Fig. 3; showing the means for controlling any of the players; Fig. 5 is a fragmentary sectional view showing a modified form of a player; Fig. 6 is an enlarged plan view of a player showing the catching arms or mitt; Fig. 7 is an enlarged and fragmentary view of the left hand end of Fig. 2, showing means for controlling the base running mechanism; Fig. 8 is an enlarged sectional view of the means for controlling the batting mechanism; and Fig. 9 is a plan view with cover of the table or field removed.

Referring to the drawings 1 represents the table, the surface of which must be level and smooth and preferably covered with cloth, similar to that with which billiard tables are covered. The table, though shown square in form, may be of any other desired shape and is provided at its bottom with base boards 2, around its outer and lower edge of sufficient depth to protect the operating mechanism to be hereinafter described underneath. Upon the upper surface of the table 1 and slightly removed from its outer edge is placed a flange or curb 3 which serves as an inclosure and prevents the ball B from leaving the table when batted or thrown. Arranged about the table in positions approximately the same as the players in a regular game of base ball, are nine players of which 4 is the catcher, 5 the pitcher, 6 the first baseman, 7 the second baseman, 8 the short stop, 9 the third baseman, 10 the left fielder, 11 the right fielder, and 12 the center fielder. All of these players are identically the same in construction, excepting the pitcher 5 who is substantially the same as the other players minus the catching arms or mitt. Each of these nine players is controlled from the same side of the table by apparatus to be hereinafter described for the purpose of having the game played by two people, but it is manifest that the controlling mechanism may be placed in any position desired so that with a large table, as many as nine people may handle the players, each playing one position.

Referring now to Figs. 3 and 4, each of applicants' players is constructed by having a cylindrical piece 13 whose upper surface is flush with the top of the table, the part exposed being circular in form and having a narrow slot 14 through its center. In this slot and fastened at its lower end is a spring

wire 15, the upper end of which is flattened and slightly cupped to fit the surface of a small steel ball B. While I have shown the spring construction, said spring 15 may be 5 displaced by having, as shown in Fig. 5, a thin metal arm 15' pivoted by means of a staple 15''. The lower end of the cylindrical piece 13 is bored out, into which is fitted a loosely sliding plunger 16, the upper end 10 of which is in contact with the lower end of the wire 15 or metal arm 15'. Fastened on the under side of the table 1 is a bracket 17 suitably bored to receive the cylindrical piece 13 and permit of its rotation. Upon 15 the lower end of the cylindrical piece 13 is secured a grooved pulley 18, the bracket 17 carrying the cylindrical piece 13 having cast integral therewith an extension 19 to which is pivoted a small bell crank 20, the upper 20 arm of which is in contact with and supports the plunger 16. Attached to the other arm of the bell crank 20 and secured to the under surface of the table is a helical spring 21, serving to place the tension upon the 25 operating mechanism, to be presently described. At the side of the table and projecting slightly above the upper edge of the flange or curb 3 is a button 22 with a knurled edge which forms the upper end of 30 a spindle 23 projecting through the surface of the table and resting upon one end of a bell crank 24. The spindle is carried and held in position by any suitable bracket 25, and is free to revolve in said bracket and 35 have an up and down movement within fixed limits. The lower arm of the bell crank 24 is connected by means of a wire 26 with the lower arm of the bell crank 20. 27 is a pulley attached to the lower end of the 40 spindle and above the bell crank 24, said pulley 27 being connected by means of an endless belt 28 with the pulley 18 attached to the cylindrical piece 13.

From the foregoing disclosure it will be 45 readily seen that by rotating the button 22 with its spindle 23, through pulleys 27, 18, and belt 28, the cylindrical piece 13 forming the player may be turned in any desired position. The spindle 23 being free to move 50 up and down, a slight blow on the top of the button 22 will transmit through the two bell cranks 24 and 20 and connecting wire 26, an upward motion to the plunger 16 which, being in contact with the wire 15 or metal piece 15', will cause the upper end of 55 the wire or metal piece to move upward and forward and propel a ball resting against the upper end of the same forward with a velocity depending upon the force of the blow. The upper surface of the cylindrical piece 13 is fitted with a shallow groove deepening toward the normal position of the thrower 15 or 15', and designed to cause the ball to rest against the thrower. The 60 shape of the upper end of the thrower 15 or

15', and the manner in which the thrower moves, together with the form of the groove in the upper end of the piece 13, gives the ball when propelled, as described above, a tendency to rise above the surface of the 70 table, and as the result of this, the ball may be thrown on a fly from one player to another. This feature is also desirable when it is necessary to throw the ball across the line of the pitcher, as from the catcher to 75 second base.

All of the cylindrical pieces 13, representing the players, with the exception of the pitcher, are provided with a mitt or catching device 29, which comprises a piece of wire 80 or sheet brass bent and formed as shown in Fig. 6. The mitt 29 is secured to the upper disk end of the cylindrical piece 13 by two wires 30 passing through holes in the disk. These wires or brass pieces 29 catch and 85 hold the ball when it enters between the outer ends of the same, until ejected by the thrower 15 or 15', as above described.

Referring now to Figs. 1, 8 and 9, 31 is a bat controlled from the opposite side of the 90 table from that of the players, said bat being rigidly connected to the spindle 32 which passes through and is rotatably supported in the guide 33 in the table 1. At the under and lower end of the spindle 32 95 are secured two pulleys 34 and 35. Secured at one end and coiled around the pulley 34 is a pull string 36 having a stop and pull button 37. Attached to the pulley 35 and oppositely wound from string 36 is another 100 string 38 whose free end is connected by means of a spring 39 to the base board 2. From the foregoing disclosure of the batting mechanism, the person handling the bat can at will strike the ball with a heavy or light 105 blow by drawing back the bat by means of the pull string 36 a greater or less arc of the circle, as the force of the blow is controlled by the tension of the spring 39. The bat has its front surface beveled similar to a 110 golf iron, so that the ball may be batted on the fly. The spring 39 holds the bat in its normal position, which is against the stop pin 40.

The mechanism for operating the runners 115 between the bases is as follows, and is shown best in Figs. 1, 2 and 7. The table 1 is provided with a narrow slot 41 which connects the bases and is not more than one sixteenth of an inch wide so as not to deflect the ball 120 when the same is rolling across the table. Under this slot 41 and arranged one over the other, are four endless belts 42, 43, 44 and 45 of suitable material (see Fig. 7) which pass over four distinct series of pulleys 46, each series of four pulleys one above the other, being placed at the four corners of the diamond, that is, the home plate, first, second and third bases. These pulleys 46 are carried by a shaft 47 and are so arranged 125 130

that each spindle has three loose pulleys and one keyed and rotatable with the shaft 47. Secured to the bottom of the shaft is a pulley 48 which is connected by means of an endless belt 49 to a pulley 50 fixed on the lower end of the rotary spindle 51, provided at its upper end with a turning crank or button 52. Attached to each one of the superimposed belts 42, 43, 44 and 45, is a vertical wire or pin 53 slightly offset from the belt, which projects through the slot 41 a little above the surface of the table 1, and on this pin is placed a miniature representative of a base runner.

15 Each of the belts 42, 43, 44 and 45 will pass over one fixed pulley and three loose pulleys. That is, the belt 42 which passes over the pulley 46 fixed to the shaft at the home plate will pass over loose pulleys on the shafts 47, at first, second and third bases, and will be controlled by the turning crank 54, while the belt 43 which passes over the pulley 46 fixed to shaft 47 at the first base will pass over loose pulleys on the shafts 47 at second and third bases and home plate, and will be controlled by turning crank 55. Likewise, belt 44 passing over pulley fixed on shaft at second base, passes over loose pulleys on shafts at third base, home, and 30 first base, and is controlled by turning crank 56; and belt 45 passes over pulley fixed to shaft at third base, and over loose pulleys at home plate, first and second bases, and is controlled by turning crank 57. It will be seen that by this means, the four belts 42, 43, 44 and 45 may be circulated around the diamond or four bases in either direction and independent of one another, and imitate in a very realistic manner, all the individualities of actual base runners.

40 From an examination of the detailed construction and mode of operation, it will be seen that any player may catch the ball and throw it to any other player. Furthermore, 45 the ball may be thrown by the pitcher over the home plate, or not, at will, the batter may bat the ball to any part of the field, depending upon his skill, and the base runner may be moved forward or backward, or 50 if several runners are in action any one of them may be moved forward or backward.

The only exception and difference from an actual game of baseball is that the players cannot run or pursue the ball, and all the 55 rules of the regular game are adhered to, with the exception that a passed ball may be picked up by the person playing the outs and give it to the player who would be supposed to get the ball in a regular game.

50 If desired, sprockets and link chains may be used instead of the pulleys 46, and the four endless belts 42, 43, 44 and 45, respectively.

We have also described above, the pitcher 65 as not being provided with a mitt like the

rest of the players; but if so desired the pitcher likewise may have a mitt, the construction of which would be the same as that of the rest of the players.

What we claim is:—

1. In an apparatus of the character described, a table having a field, a swinging bat, means for oscillating said bat, a catcher, a pitcher having means for receiving a ball, means for moving said pitcher, means on 70 said pitcher for impelling the ball, rotatable outfielders with means for catching an impelled ball, and ball impelling means on each of said outfielders.

2. In an apparatus of the character described, a table having a field, a swinging bat, means for oscillating said bat, a catcher, a pitcher having means for receiving a ball, means for moving said pitcher, means on 75 said pitcher for impelling the ball, rotatable 80 outfielders with wire mits for catching an impelled ball, and ball impelling means on each of said outfielders.

3. In an apparatus of the character described, a table having a field, a swinging 90 bat, means for oscillating said bat, a catcher, a pitcher having means for receiving a ball, combined means for oscillating said pitcher and impelling the ball, rotatable outfielders with means for catching an impelled ball, 95 and ball impelling means on each of said outfielders.

4. In an apparatus of the character described, a table having a field, a swinging bat, means for oscillating said bat, a catcher, 100 a pitcher having means for receiving a ball, means for moving said pitcher, means on said pitcher for impelling the ball, rotatable outfielders with means for catching an impelled ball, and ball impelling means on 105 each of said outfielders, and means connected to each of said outfielders for rotating said outfielders and actuating the ball impelling means.

5. In an apparatus of the character described, a table having a field, a swinging bat, means for oscillating said bat, a catcher, a pitcher having means for receiving a ball, means for moving said pitcher, means on 110 said pitcher for impelling the ball, rotatable 115 outfielders with means for catching an impelled ball, and ball impelling means on each of said outfielders, separate and independent means connected to each of said outfielders for rotating said outfielders and actuating the ball impelling means.

6. A baseball game apparatus, comprising a rotary outfielder having a catching mitt and ball impelling means, and a single shaft or spindle controlling the rotary movement 120 of said outfielder and ball impelling means.

7. In an apparatus of the character described, a table having a field, a diamond on said field circumscribed by a narrow slot, a pitcher, a batter, a catcher, outfielders on 125 130

said field, a series of superimposed endless belts passing around the corners of the diamond and below the slot, means for attaching runners to said belts, and means for operating simultaneously and independently said belts.

8. In an apparatus of the character described, a table having a field, a diamond on said field circumscribed by a narrow slot in 10 the table, a pitcher, a batter, a catcher, out-fielders on said field; four superimposed endless belts passing around the corners of the diamond below the slot in the table, means for attaching independent runners to said 15 belts through the slot, and separate and independent means for operating simultaneously and independently said belts and runners about the diamond field.

9. In an apparatus of the character described, a table having a field, a diamond on 20 said field circumscribed by a narrow slot in the table, a pitcher, a batter, a catcher, out-fielders on said field, a shaft at each corner of the diamond having one fixed and three 25 loose pulleys thereon, four superimposed endless belts passing around the corners of the diamond and carried by said fixed and loose pulleys, means for attaching runners to said belts, and means connected with said 30 shafts for operating simultaneously and independently said belts and runners about the diamond field.

10. In an apparatus of the character described, a table having a field, a diamond on 35 said field circumscribed by a slot in the table, a pitcher, a batter, a catcher, out-fielders on said field, a shaft at each corner of the diamond having one fixed and three loose pulleys thereon, four endless belts passing 40 around the corners of the diamond and carried by said fixed and loose pulleys, means for attaching runners to said belts and projecting through the slot, and separate and independent means connected with and rotating the fixed pulley on each of the shafts 45 for operating independently and in either direction said belts.

11. In an apparatus of the character described for playing baseball comprising a table having a field, a diamond on said field 50 circumscribed by a slot in the table, four endless belts passing around the corners of the diamond below the table and slot, means for attaching runners to said belts through the slot, and means connected to each of said 55 belts for independently moving said belts and runners backward or forward.

In testimony whereof we affix our signatures in presence of two witnesses.
